UNITED STATES PATENT OFFICE.

GEORGE A. LOCKE, OF MASPETH, NEW YORK, ASSIGNOR TO WESTERN ELECTRIC COMPANY, INCORPORATED, OF NEW YORK, N. Y., A CORPORATION OF NEW YORK.

PRINTING TELEGRAPHY.

Application filed February 1, 1922. Serial No. 533,277.

To all whom it may concern:

Be it known that I, GEORGE A. LOCKE, a citizen of the United States, residing at Maspeth, in the county of Queens, State of New York, have invented certain new and useful Improvements in Printing Telegraphy, of which the following is a full, clear, concise, and exact description.

This invention relates to telegraph systems.

An object of the invention is to provide a system whereby a plurality of telegraph messages originating at separate stations may be transmitted over a plurality of branch lines or extension circuits to main or central stations, where synchronous multiplex apparatus is located for automatically and simultaneously transferring the code combinations of message impulses to a line connecting the central stations.

Another object is the provision of means associated with the synchronous multiplex apparatus at the central stations for providing a complete overlap between the selections received from the synchronous multiplex apparatus and those transmitted to the extension circuits or branch lines.

The invention provides synchronous multiplex and start-stop apparatus at the central stations with means associated therewith such as a plurality of groups of relays, one group of which is designed to remain energized until deenergized due to the receipt of a succeeding selection which accordingly changes the polarity of the selecting impulse for providing a complete overlap between the selections received from the synchronous multiplex apparatus and those transmitted by the start-stop apparatus to the extension circuit.

The invention is illustrated in the accompanying drawing which represents one embodiment of the invention and when arranged so that Fig. 1 is to the left of Fig. 2 a complete system is shown diagrammatically.

The invention, in the embodiment disclosed, comprises a branch office A which is connected with a main or central office B by an extension circuit or branch line 6, a central or main station C connected with the

main station B by a line 7 equipped with duplex apparatus and a distant branch office D which, like branch office A, is connected with the associated central station C by an extension circuit 8.

At the branch office A there are located transmitting and receiving equipments E and F respectively, being shown diagrammatically. The extension circuit 6 may be a pair of line conductors or a single line conductor equipped with duplex apparatus, as illustrated in the drawings. Both of the central stations B and C are provided with receiving distributors G and H of the start-stop type to receive the code combinations of message impulses from the respective substations or the branch offices and transfer them to the multiplex synchronous distributors I and L also located at the offices B and C respectively, through the instrumentalities of a series of condensers and a plurality of groups of storing relays. Also located at the central offices are the synchronous distributors K and M, each of which serves to receive the signaling impulses from the line conductor 7 connecting these two stations and to transfer the same to the start-stop distributors N and R respectively, through the instrumentalities of a plurality of groups of relays which, according to the present invention, provide a complete overlap between the selections received on the synchronous multiplex distributors and those transmitted to the extension circuits by the start-stop distributors associated therewith. Branch office D, like branch office A, is provided with a transmitting distributor P and a receiving distributor Q, which serve their respective purposes. For the sake of clarifying and simplifying the drawings, the apparatus common to one channel has been shown in detail, while that individual to the other channel has been shown schematically.

The transmitting equipment E comprises an intermittently rotary distributor 10 having a brush arm 11 which carries a pair of brushes 12 and 13 arranged to make contact with rings 14, 15, 16 and 17. The outer ring 17 is divided into a plurality of segments 18, 19, 20, 21, 22 and 23, which are

connected with the respective contacts of a transmitter shown diagrammatically at 24. In order that the brush arm 11 will be stopped and released once per revolution, a 5 release magnet 27 is provided which is under the control of a start relay 28 controlled by a common contact on the transmitter 24. The transmitter 24 consists of a plurality of movable contacts 30, 31, 32, 33 and 34 which 10 are connected to the respective segments forming the outer ring 17 of the distributor 10. Also arranged in the transmitter 24 is a common contact 35 which, as previously stated, controls the energization of the start 15 relay 28. Although the transmitter 24 has been shown diagrammatically as a keyboard transmitter, any well-known type of transmitter may be substituted therefor which will provide equally good results.

20 At the central office B there is shown a receiving distributor G of the start-stop type and a synchronously operated distributor I which has its continuous ring 95 connected to the apex of the ratio arms which includes 25 the receiving relay 99 forming a part of the duplex equipment associated with the line conductor 7. The line relay 99 responds only to incoming impulses and is non-responsive to outgoing impulses. Upon the operation 30 of the multiplex distributor I, this relay will not respond to impulses which may be transferred thereto from the start-stop distributor G.

The start-stop distributor G comprises an 35 outer ring 44 and an inner ring 40. Forming a part of the outer ring is a plurality of segments 47, 48, 49, 50, 51, 52 and 53, the first five of which correspond to respective ones of the segments on the transmitting distributor 10. By the proper orientation of these segments and inasmuch as they are smaller than the transmitting segments of the transmitting distributor 10, the central portion of the signal impulse transmitted 40 over the extension circuit 6 to the line relay 37 will be picked up for each segment of the sending face at the branch office A. The distributor G also comprises a brush arm 41 carrying brush 42 which is held against rotation by a release latch under the control of 45 release magnet 39.

Interposed between the start-stop distributor G and the multiplex or synchronously operated distributor I, are a set of condensers 55 in combination with a single group of storing relays operable in accordance with the signals transmitted and controlled by a series of transfer relays under the control of both the start-stop distributor G and the 60 multiplex distributor I. The set of condensers and the single group of storing relays serve to provide a complete overlap between the selections received from the start-stop distributor G and those transmitted out 65 over the line 7 by the multiplex distributor

I irrespective of what the phase relation is between the brush arm of the multiplex distributor I and the brush arm of distributor G, providing, of course, that the speed of the brush arm of the start-stop distributor is 70 equal to or slightly less than that of the brush arm of the multiplex distributor I. The condensers 56, 57, 58, 59 and 60 are connected directly to the receiving segments forming the outer ring of the distributor G 75 and will be charged in accordance with the operation of relay 38. During certain periods of operation however, the impulses received on the segments 47 to 51 inclusive, will be transferred directly through the armatures and contacts of the transfer relays 70, 71 and 72 to the right-hand windings of the set of storing relays 76 to 80 inclusive, as will be more clearly described hereinafter. The energization of the transfer relays 70, 71 80 and 72 is controlled jointly by the start-stop distributor G and the multiplex distributor I, so that no mutilation or piling up of the signaling impulses will result should one distributor be slightly out of phase with respect to that of the other. Upon the energization of the storing relays 76 to 80 inclusive, a locking circuit is established therefor which is under the control of the multiplex distributor I and which will be released once 85 per revolution thereof. After a set of impulses have been transmitted from the distributor G to the condensers 56 to 60 and upon the release of the transfer relays 70, 71 and 72, a discharge circuit is established for 90 these condensers extending through the right-hand winding of the corresponding ones of the storing relays 76 to 80 which thereupon attract their armatures and establish a locking circuit therefor. These relays 100 will be locked up through their own contacts and left-hand windings, thus after their initial energization are maintained energized independent of the condensers 56 to 60. It is through the contacts of the relays 105 76 to 80 that the polarity of the impulses 110 corresponding to the various characters is varied.

In order that the impulses will be transferred from the respective parts of the circuit so that no mutilation of signals will result, such transfer is under the joint control of the start-stop distributor G and the synchronous multiplex distributor I as will be more clearly described hereinafter.

The apparatus just described constitutes the equipment located at the central or main station B and which serves to transmit impulses from the branch office A to the line conductor 7 and thence to the central office C from whence the message impulses are transmitted to the distant branch office D.

The apparatus at the central office C which receives the signals transmitted from the transmitting apparatus located at the 130

central office B comprises a multiplex distributor M and a distributor of the start-stop type R. The multiplex distributor M comprises, among other parts, a continuous 5 ring 113 and an outer ring which is divided into a plurality of segments 107, 108, 109, 111 and 112. Like the distributor I a continuously revolving brush arm 102 carrying brushes 103 and 104 10 is provided. Connected to the smaller segments forming a part of the outer ring are the windings of a set of storing relays 115, 118, 121, 124 and 127 which serve in combination with the other two sets of 15 storing relays 114, 117, 120, 123, 126 and 116, 119, 122, 125 and 128 to provide a complete overlap between the selections transmitted from the multiplex distributor M and those transmitted over the extension circuit 20 8 by the start-stop distributor R.

The start-stop distributor R comprises an outer ring divided into a plurality of smaller segments 132, 133, 134, 135, 136 and 137. The first five of these segments are 25 connected to the right-hand armatures of the storing relays 115, 118, 121, 124 and 127 which, upon their energization, are locked whereby the armatures thereof remain in the position set until due to a subsequent 30 selection they are released for transmitting an effect opposite to that when they were energized. For bridging the outer ring of the distributor R, with the inner ring 138, the distributor has a brush 130 carried by a 25 brush arm 129 which is normally held against rotation by a latch under the control of a release magnet 131. The release magnet 131 is controlled through contacts on the relays 114, 117, 120, 123 and 126 so that 40 upon the energization of any one of these relays an energizing circuit for release magnet 131 is established for causing the release of the brush arm 129.

The receiving equipment Q at the branch 45 office D comprises a receiving printer diagrammatically shown at 155 which comprises the usual selecting magnets 156, 157, 158, 159 and 160 and the printing magnet 168. The respective magnets have their windings connected to the segments 161, 162, 163, 164 and 165 forming a part of the outer ring of the receiving distributor. The distributor like the distributor G has a brush arm 147 carrying a brush 148 which 55 is arranged to bridge the segments forming a part of the outer ring with the segments 154, 166 and 152 for controlling the energization of the respective ones of the selecting magnets depending upon the energization of relay 151 which, in turn, is controlled by the line relay 146 connected to the extension circuit 8.

Inasmuch as the apparatus associated with the other channel of the system is identical with the equipment just described, further

description thereof is considered unnecessary here. However, the rectangles designated by the characters S and T represent the equipment intermediate the distributors G and I and M and R respectively, which as 70 previously described, are shown diagrammatically for the sake of clarifying the drawings.

The operation of the equipment just described is as follows: Assume, for the sake of clearness, that the branch office A desires to communicate with the branch office D, in which case the transmitter 24 will be operated to set up a particular combination depending upon the message desired to be 75 transmitted. Let it also be assumed that it is desired to transmit a character in which contacts 30, 32 and 34 of the transmitter 24 are actuated for closing their respective contacts. 80

As previously described, upon the operation of the transmitter 24, contact 35 will be closed for causing the energization of the start relay 28, the energizing circuit of 85 which extends from battery through the left-hand winding thereof, contact 35, segment 15, brush 13 and the segment 14 of the transmitting distributor 10 to ground. The start relay 28 is thereupon energized and is locked up over a circuit under the control of brush 90 13. Upon the energization of start relay 28 an energizing circuit is established for release magnet 27 which, in operating, withdraws the release latch under its control 95 from engagement with the brush arm 11, which is thereupon free to rotate whereupon the brush 12 consecutively completes circuits extending from the segments 18, 19, 20, 21 and 22 and the contacts of the transmitter 24 which have been operated through the winding of the pole changing relay 29. The pole changing relay 29 is energized 100 upon the passage of the brush 12 over the segment to which one of the closed contacts of the transmitter 24 is connected for applying to the line 6 an impulse of a polarity corresponding to that normally applied thereto. The instant the brush 12 passes off segment 23 an open circuit condition is established 105 whereby the pole changing relay 29 reverses the position of its armature and connects the positive source of current with the apex of the ratio arms to which the receiving relay 36 is connected, but which does not respond to outgoing impulses. Relay 37 located at the central office B does however, 110 respond to such change in polarity and reverses the position of its armature whereby the energizing circuit of relay 38 is broken, 115 consequently an energizing circuit for the release magnet 39 of the distributor G is established extending from battery through the winding of release magnet 39, segment 53, brush 42, segment 54 of the distributor G and the winding of relay 61 to ground. 120

Inasmuch as the apparatus associated with the other channel of the system is identical with the equipment just described, further 125

- 1 Relay 61 in attracting its armature causes a momentary charging of the condenser 67 which is normally short-circuited by the high resistance 68, through the left-hand 5 winding of relay 62. Relay 62 thereupon attracts its armatures which conditions an energizing circuit for relay 63 but which is not completed until the bridging of the segments 52 and 46 by the brush 42. At the 10 right-hand armature and contact of this relay, an energizing circuit is established for the transfer relays 70, 71 and 72 extending from battery through the right-hand winding of relay 62, armature and contact thereof, windings of relays 72, 71 and 70 in series and the right-hand armature and contact of relay 66 to ground. Relay 62 is locked up over the circuit just traced and is maintained 15 energized until the energization of relay 66.
- 20 The release magnet 39 being energized, the brush arm 41 is thereby released for rotation. Owing to the withdrawal of the release latch under its control and contact 30 of the transmitter 24 being closed an energizing 25 circuit for the pole changing relay 29 is established upon the passage of the brush 12 over the segment 18 of the transmitting distributor 10, thus connecting the negative pole of the battery with the line conductor 30 6 and consequently causing the reversal of the armature of receiving relay 37 to the position shown in the drawing which in turn causes the energization of relay 38. The closure of the front contact of relay 38 establishes 35 upon the passage of the brush 42 over segment 47 a charging circuit for the condenser 56 whereupon this condenser is charged. The contact 31 of the transmitter 24 being open, the pole changing relay 29 40 is caused to reverse the position of its armature upon the passage of the brush 12 over the segment 19 to which contact 31 of the transmitter is connected. Similarly the receiving relay 37 at office B reverses the 45 position of its armature and consequently causes the deenergization of relay 38. Thus, upon the passage of the brush 42 over segment 48 of the distributor G, the condenser 57 will not be charged. Contacts 32 and 34 of the 50 transmitter 24 being closed, conditions similar to those described in connection with contact 30 will be established for causing the charging of condensers 58 and 60 in accordance with the energization of relay 38, 55 upon the passage of the brush 42 over the segments to which these condensers are connected. Condenser 59 will however, not be charged owing to contact 33 of the transmitter 24 being open so that an open-circuit 60 condition is established upon the passage of the brush 42 over the segment individual thereto.
- 65 Just prior to the completion of the cycle of rotation of the brush arm 41, an energizing circuit is established for relay 63 extend-
- ing from battery through the armature and contact of relay 64, winding of relay 63, front contact of relay 62, segment 52, brush 42 and segment 46 of the distributor G to ground. Relay 63 is thereupon energized 70 and locked up and establishes at its left-hand contact a short circuit for the condenser 67, otherwise, no effect is produced due to the energization of this relay.
- The brush 88 of the multiplex distributor 75 I in passing over segment 96 completes an energizing circuit for relay 65 extending from battery through ring 98, brush 88, segment 96 of the distributor I, contact 69 on the relay 66 and the winding of relay 65 to ground. Relay 65 in closing its left-hand contact opens the locking circuit of the relays 76 to 80 inclusive, thereby restoring any one of these relays which have previously 80 been energized to normal and also establishes an auxiliary locking circuit for relay 62 for preventing the release of this relay. Upon the closure of the right-hand contact of relay 65 an energizing circuit for relay 66 is 85 established extending from battery through the ring 98, brush 88, segment 96, right-hand contact and armature of relay 65 and the winding of relay 66 to ground. Relay 66 in energizing opens the original energizing circuit of relay 65 which thereupon 90 releases its armature and again conditions the locking circuit of the storing relays 76 to 80 inclusive, while at the right-hand armature the locking circuit of relay 62 is broken thereby causing the deenergization of this 95 relay and consequently the deenergization of transfer relays 70, 71 and 72. Upon the release of the transfer relays 70, 71 and 72, a discharge circuit is established for the condensers 56, 58 and 60 through the armatures 100 and contacts of the transfer relays 70, 71 and 72 to the right-hand winding of the storing relays 76, 78 and 80. These relays will be thus energized and locked up over a circuit from battery through the left-hand 105 armature and winding thereof and the left-hand normal contact of relay 65 to ground. Inasmuch as the condensers 57 and 59 for the particular selection chosen were not charged, no results will be produced on the 110 relays 77 and 79 corresponding to these condensers, upon the deenergization of the transfer relays 70, 71 and 72. Relay 62 in closing its left-hand normal contact establishes an energizing circuit for relay 64 115 which is completed upon the passage of the brush 42 over segments 52 and 46 of the distributor G during the next cycle of rotation.
- When the brush arms 41 and 87 of the start-stop distributor G and multiplex distributor I respectively, are practically coincident, that is, they have the same phase relation or the brush arm 41 is about to engage the segments 53 and 54 at the time the brush 120 88 is passing over segment 96, relay 62 is 125

prevented from deenergizing upon the operation of relays 65 and 66, as previously described, for transferring the impulses stored in the condensers 56 to 60 inclusive, due to the energization of relay 63. Upon the engagement of the brush 42 with the segments 53 and 54, and due to the energization of relay 61, a sustained impulse will traverse the left-hand winding of relay 62 which will be equal to the length of the segments 53 and 54. The circuit of the sustained impulses extends from battery through the left-hand winding of relay 62, left-hand contact and armature of relay 63 and the armature and contact of relay 61 which is maintained energized as long as relay 38 is deenergized, which, as previously described, is controlled from contacts on the relay 37 in turn controlled from the branch office A. By the provision of such an arrangement the control of the transfer is now such that the impulses stored in the condensers 56 to 60 will be transferred to the storing relays 76 to 80 at the proper time. During a certain cycle of operation of the distributors the brush 88 will pass over segment 96 at a period in advance of the passage of the brush 42 over segments 52 and 46 of the distributor G in which case the relay 62 will have been deenergized and accordingly the transfer relays 70, 71 and 72 will be deenergized for transferring the impulses stored in the condensers 56 to 60 to the storing relays 76 to 80 inclusive. However, upon the passage of the brush 42 over segments 52 and 46, an energizing circuit is established for relay 64 which, as previously described, controls the locking circuit of relay 63. The energizing circuit for relay 64 extends from battery through the winding thereof, left-hand normal contact and armature of relay 62, segment 52, brush 42 and segment 46 of the distributor G to ground. Relay 64 in energizing merely opens the locking circuit for relay 63 which is then restored to normal for removing the short circuit from about the condenser 67. Thus, upon the engagement of the brush 42 with the segments 53 and 54 conditions similar to that described for the initial operation of the system will be brought about, that is, the condenser 67 will be charged and a momentary surge of current through the winding of relay 62 produced for causing the energization and locking of this relay. Upon the passage of the brush 89 of the multiplex distributor I over the respective ones of the segments to which these relays are connected, a polarity of battery depending upon the energization of the storing relays 76 to 80 will be applied to the apex of the ratio arms to which receiving relay 99 is connected and thence over the line conductor 7 to the central station C.

Upon the passage of the brush 89 over segment 94 to which the armature of storing relay 76 is connected, an impulse of positive polarity will be transmitted to the central station C which passes through the windings of the receiving relay 101 for causing the reversal of its armature. The negative pole of the battery associated with the contacts of this relay is thereupon connected with ring 113 of the distributor M so that upon the passage of the brush 104 over the segment to which the storing relay 115 is connected this relay will be energized over a circuit extending from battery, upper contact and armature of receiving relay 101, ring 113, brush 104, segment 107, right-hand armature and normal contact of relay 114, winding of relay 115 to ground. Relay 115 in closing its left-hand contact establishes an energizing circuit for itself extending from battery through the left-hand armature and contact of relay 116, winding of relay 114, left-hand armature and contact and the winding of relay 115 to ground. Relay 114 being energized upon the establishment of the circuit just traced, opens upon the attraction of its armature the initial energizing circuit of relay 115 and closes at its right-hand alternate contact an energizing circuit for relay 116 which, as will be more clearly described hereinafter, is not energized until the reception of a subsequent selection of a polarity opposite to the previous selection which caused the energization of relay 115. It is thus seen that the relay 115 will remain in the position set until the reception of a subsequent selecting unit differing in polarity from the one which previously caused the energization of this relay. As the brush arm 87 continues to rotate, conditions depending upon the position of the armatures of the storing relays 76 to 80 inclusive, will be set up for causing the corresponding positioning of the armature of receiving relay 101 at the central office C. Thus upon the passage of the brush 104 over the segments to which the storing relays 118, 121, 124 and 127 are normally connected, these relays will be energized depending upon the energization of the storing relays of the second set located at the central office B. For the particular selection chosen, storing relays 121 and 127 will be energized over circuits similar to that traced in connection with storing relay 115. The energized ones of these storing relays will also be locked up through contacts in a manner similar to that described in connection with the storing relay 115. Upon the passage of the brush 104 over the segment to which the storing relays 118 and 124 are connected these relays will not be energized owing to the position of the armature of relay 101. However, had these relays been previously energized, an energizing circuit would be established for the re-

lays 119 and 125 of the second set of storing relays, the circuit of which extends from battery, windings of these relays, right-hand alternate contact and armature of relay 117, segment 108, brush 104, ring 113, armature and lower contact of relay 101 to ground.

Following the passage of the brush 89 over segment 90 of the multiplex distributor 10 I, the brush 88 engages segment 96, whereupon an energizing circuit is established for relay 65 in the manner previously described, which in turn causes the energization of relay 66 and the opening of the locking circuit of the storing relays 76 to 80 inclusive, which had been previously energized. Similarly, relay 66 in opening its right-hand contact causes the deenergization of the transfer relays 70, 71 and 72 for transferring the impulses stored in the condensers 56 to 60 in accordance with the next selection to the storing relays 76 to 80.

Following the passage of the brush 104 of the multiplex distributor M over segment 25 112, brush 103 bridges segment 105 with ring 106, whereupon an energizing circuit is established for the release magnet 131 of the start-stop distributor R. This circuit extends from battery through the winding 30 of the release magnet 131, conductor 139, segment 105, brush 103 and ring 106 to ground. Release magnet 131 upon being energized withdraws its release latch from engagement with the brush arm 129 thereby 35 permitting the rotation thereof. The brush 130 carried by the brush arm 129 consecutively connects the segments 132, 133, 134, 135 and 136, which are connected with respective armatures of the storing relays 115, 40 118, 121, 124 and 127 in circuit with the winding of the pole changing relay 142. Prior to the engagement of the brush 130 with the segment 132 and upon the passage of this brush off segment 137, pole changing 45 relay 142 is deenergized thereby impressing on the extension circuit 8 an impulse of a positive polarity which, upon being received at the branch office D, causes the reversal of the armature of the receiving relay 146. 50 Relay 146 in reversing the position of its armature causes the deenergization of relay 151 which, in turn, closes through its back contact an energizing circuit for the release magnet 150 of the receiving distributor, thus releasing the brush arm 147 for rotation.

Upon the passage of the brush 130 over segment 132, and owing to the fact that the storing relay 115 is energized, an energizing 60 circuit is established for the pole changing relay 142 extending from battery to the ring 138, brush 130, segment 132, of the distributor R, right-hand armature and contact of storing relay 114 and the winding of the 65 pole changing relay 142 to ground. The

closure of such a circuit causes the energization of the pole changing relay 142, which impresses on the extension circuit 8 an impulse of a negative polarity for causing the reversal of the position of the armature of 70 the receiving relay 146 to the position shown in the drawing, consequently causing the energization of relay 151. Relay 151 being now energized upon the passage of the brush 148 over segment 161, selecting magnet 156 75 connected to this segment will be energized over a circuit extending from battery through the winding of this magnet, segment 161, brush 148, ring 154 and the alternate contact and armature of relay 151 to 80 ground. The movement of the selecting bar under the control of this magnet will be effected at this time.

The brush 130 in passing over segment 133 and inasmuch as storing relay 118 is not 85 energized causes the pole changing relay 142 to reverse the position of its armature and impresses on the extension circuit 8 an impulse of a positive polarity. Similarly, upon the passage of the brush 148 over segment 162 to which the selecting magnet 157 is connected, an open circuit condition is established owing to the fact that the receiving relay 146 has reversed the position of its armature and, in turn, caused the deenergization of relay 151. Conditions similar to those just described for selecting magnet 156 will be established upon the passage of the brush 148 over segments 163 and 165 respectively, for causing the energization of 90 the corresponding selecting magnets 158 and 160 of the receiving printer 155. However, since the storing relay 124 is not energized for this selection, no effect will be produced 95 on the selecting magnet 159 upon the passage of the brush 148 over segment 164 to which this selecting magnet is connected.

Following the passage of the brush 148 off segment 165 and the passage thereof over segments 166 and 167 a circuit is completed extending from battery through the winding of printing magnet 168, segment 167, brush 148 and segment 166 to ground. Thus, the signals transmitted from the branch office A will be recorded on the receiving printer 155 at the branch office D over one channel of the line conductor 7 equipped for duplex operation.

Although the invention has been illustrated in connection with a system wherein 120 code combinations of message impulses originating at a branch office are transferred to a main or central office at which synchronous printing telegraph apparatus is located and thence over a conductor equipped for duplex operation to a second central or main station having equipment similar to that just referred to from which it is transferred over an extension circuit to a distant office, it is, 125 of course, obvious that the invention may 130

be readily applied to other types of systems without departing from the spirit and scope of the present invention.

What is claimed is:

5. 1. In combination, a line, a distributing mechanism for distributing selecting units to said line, and electromagnetic means operatively energized operated in response to said selecting units and retained energized 10 until the receipt of selecting units differing in character from those that caused initial operation thereof.
- 15 2. In combination, a main line, an extension circuit, distributing mechanism for distributing code combinations of message impulses received from the main line to the extension circuit, and a plurality of groups of electromagnetic devices associated with said distributing mechanism for storing simultaneously records of successive code combinations to provide a complete overlap between the selections received from the main line and those transmitted to the extension circuit.
- 20 3. In a signaling system, receiving and transmitting distributor mechanisms, signal storing means comprising a plurality of groups of electromagnetic devices intermediate such mechanisms for storing simultaneously records of successive code combinations of message impulses to provide a complete overlap between the selections received by the receiving distributor mechanism and those transmitted by the transmitting distributor mechanism.
- 25 4. In combination, a main line, an extension circuit, distributing mechanism for distributing code combinations of message impulses from the main line to the extension circuit, a plurality of groups of electromagnetic devices associated with said distributing mechanism for storing simultaneously records of successive code combinations to provide a complete overlap between the selections received from the main line and those transmitted to the extension circuit, one of said groups of devices being retained operated until released due to the receipt of

a selection of a character opposite to that which previously caused their operation. 50

5. In a printing telegraph system, a main line, a synchronous multiplex distributor associated with said main line, an extension circuit, a start-stop distributor connected thereto, a group of storing relays associated with said distributors and energized in accordance with the selections received by said multiplex distributor, and means controlled by said group of relays for retaining said relays energized until a change in the character of the selections is received. 60

6. In a printing telegraph system, a main line, a synchronous multiplex distributor associated with said main line, an extension circuit, a start-stop distributor connected thereto, a group of storing relays associated with said distributors and energized in accordance with the selections received by said multiplex distributor, and a relay individual to each of the storing relays energized upon the operation thereof for maintaining the storing relay individual thereto energized so long as selections of the same character are being received from the main line. 70

7. In a printing telegraph system, a main line, a synchronous multiplex distributor associated with said main line, an extension circuit, a start-stop distributor connected thereto, a group of storing relays associated with said distributors and energized in accordance with the selections received by said multiplex distributor, a relay individual to each of the storing relays and energized upon the operation thereof for maintaining the storing relay individual thereto energized independent of signals on the main line, and means conditioned for operation upon the operation of the relay individual to the storing relay and subsequently operated due to the receipt of a selecting unit for causing the release of the storing relay individual thereto. 80 85 90

In witness whereof, I hereunto subscribe my name this 24th day of January A. D., 1922.

GEORGE A. LOCKE.
